[57] CLAIM

The ornamental design for an insect trap, as shown and described.

DESCRIPTION

FIG. 1 is a perspective view of an insect trap, showing my new design;

FIG. 2 is a cross-sectional view thereof, taken along line 2—2 of FIG. 1;

FIG. 3 is a top plan view thereof;

FIG. 4 is a right side, elevational view, the left side being substantially a mirror image thereof;

FIG. 5 is a bottom plan view thereof;

FIG. 6 is a rear elevational view thereof; and

FIG. 7 is a front elevational view thereof.
